UNITED STATES PATENT OFFICE.

HENRY R. ROEGLIN, OF MILWAUKEE, WISCONSIN, ASSIGNOR OF ONE-HALF TO JOHN MOLNAR, OF MILWAUKEE, WISCONSIN.

BUILDER'S TOOL.

Application filed February 6, 1922. Serial No. 534,638.

To all whom it may concern:

Be it known that I, HENRY R. ROEGLIN, a citizen of the United States, and resident of Milwaukee, in the county of Milwaukee, 5 and State of Wisconsin, have invented new and useful Improvements in Builders' Tools, of which the following is a description, reference being had to the accompanying drawings, which are a part of this specification.

10 The invention relates to builders' tools. In the usual manner of putting up buildings having wooden uprights or walls, it is necessary to have one or more men hold and 15 maintain the upright in a plumb position while another secures it to the adjacent structure. To permit the carpenter who does the nailing or fastening of the upright or wall to also bring and secure the upright 20 or wall in its proper position without a helper, I have provided an adjustable brace, engageable with the upright and with a relatively fixed support, which may be readily manipulated and whose use effects a 25 saving in labor in the erection of a building.

With the above and other objects in view the invention consists in the device herein-after described and all equivalents.

In the drawings: Fig. 1 is a side view of 30 a device embodying the invention; Fig. 2 is a front view thereof; Fig. 3 is a section taken on the line 3—3 of Fig. 2; Fig. 4 is a section taken on the line 4—4 of Fig. 2.

In the drawings the numerals 4 designate 35 aligned rods having threaded inner ends 5 upon which a turnbuckle 6 is mounted and provided with projecting pins 7 to facilitate moving it. The threaded connection between the rods 4 and the turnbuckle 6 is 40 such that turning the turnbuckle 6 in one direction causes the rods 4 to move toward each other, and in the opposite direction away from each other.

Each of the rods 4 carry a timber-engaging 45 clamp at its outer end. Each clamp includes a pair of jaws 8 pivotally mounted at their inner ends upon pivot screws 9, or other suitable pivots which are mounted in the ears 10 of complementary sections 50 11 forming a collar seated in an annular groove 12 of a nut 13 in threaded engagement with the outer threaded end 14 of the rod 4. The intermediate portions of the jaws 8 are each respectively connected by 55 screws 15 or other suitable fastening means

to the forked portions 16 of a link 17, the inner ends of said links being pivotally mounted upon pivot screws 18, or other suitable pivots, which are mounted in the ears 19 of a member 20. The member 20 has a 60 threaded bore 21 fitting end 14 of the rod and a set screw 22 engaging the rod to secure said member against rotation with respect to the rod. The jaws 8 have pointed ends 23 to engage in the timber or other material 65 forming the building structure, and the nut 13 has projecting pins 24 to facilitate turning it.

With the construction of clamp above described turning the nut 13 so as to move 70 it outward on its rod 4 produces a relative movement between said nut and the links 17 which causes said links to swing the jaws about their lower pivots and draw their outer pointed ends together so as to 75 tightly engage the structure to which the device is applied, and an inward movement of said nuts causes an outward movement of said jaws.

By way of illustrating one of the uses to 80 which the tool above described can be put, I show two timbers 25 and 26, in Fig. 1, which it is desired to secure together at right angles to each other. To accomplish this one of the jaws is clamped to the timber 25, 85 as previously described, and the other jaw is clamped to the timber 26 when the same is in an approximately upright position. Then the turnbuckle 6 is rotated to move the rods 4 with respect to each other to so 90 adjust the distance between the clamps as to bring the timber 25 to its desired plumb position and maintain it in this position while it is being nailed or otherwise secured to the timber 26. It is to be understood that 95 when sections of a wall of the so-called portable buildings are being put up several of the tools above described may be used on the wall.

I desire it to be understood that this invention is not to be limited to any specific form or arrangement of parts except in so far as such limitations are specified in the claims.

What I claim as my invention is:

1. In a building tool, the combination of 100 a pair of clamps having adjustable timber-holding and supporting jaws, and a lengthwise adjustable supporting connection between said clamps.

105

110

2. In a building tool, the combination of a sectional rod, an adjustable turnbuckle connecting the sections of said rod together, and an adjustable timber-holding and supporting jaw clamp at the outer end of each section.
3. In a building tool, the combination of a sectional rod, an adjustable turnbuckle connecting the sections of said rod together, each of said rod sections having threaded outer ends, a nut mounted on the threaded outer end of each rod, a pair of timber-holding and supporting jaws, and means operatively connected to each nut and rod for moving said jaws toward or away from each other.
4. In a building tool, the combination of a pair of rods having threaded outer ends, means for moving said rods with respect to each other, a timber-holding and supporting clamp mounted on the outer end of each rod comprising a nut mounted on the thread outer end of the rod, a pair of clamp-
- ing jaws, a collar carried by said nut and free to rotate with respect thereto, means pivotally connecting the lower ends of said jaws to said collar, and means connected to the jaws intermediate their ends and to said rod cooperating with said nut and collar to swing said jaws toward or away from each other.
5. In a building tool, the combination of a pair of rods having threaded outer ends, a turnbuckle connecting the inner ends of said rods, a timber-holding and supporting clamp mounted on the outer end of each rod comprising a nut mounted on said threaded outer end of the rod, a pair of clamping jaws, a collar carried by said nut and free to rotate with respect thereto, pivotal connections for the lower ends of said jaws with the collar, and links connected to the jaws intermediate their ends and operatively connected to said rod.

In testimony whereof I affix my signature.
HENRY R. ROEGLIN.
